UNITED STATES PATENT OFFICE.

HANS F. HOFER, OF NAGOYA, JAPAN.

WASTELESS SKEIN.

Application filed May 26, 1922. Serial No. 563,986.

To all whom it may concern:

Be it known that HANS FREDERICK HOFER, a citizen of the United States, residing at % Fuso Seishi Kabushiki Kaisha, Nishi-haru, outskirt of Nagoya City, Aichi-Prefecture, Japan, has invented certain new and useful Improvements in Wasteless Skeins, of which the following is a specification.

This invention relates to skeins of thread and more particularly to skeins of silk, and the primary object of the invention is to remedy the generally recognized fault in the ending-up of a silk skein.

Prior to the present invention the beginning and end of the thread of the skein were tied together either on to one of the lace-bands in the skein or onto a separate ending-up band. With skeins finished in this manner, close observation during the work of unwinding the silk from the skein onto spools discloses that due to the absence of a clear indication as to the unwinding direction of the skein, the unwinding operator is apt or liable to mount the skein on to the swift with the unwinding direction of the thread opposite to the correct unwinding direction. Such mistake, usually, is noticed by the operator only upon being unable to perform the uninterrupted winding off of the silk from the skein. When finally the mistake has been recognized the swift removed from the winding machine and replaced in proper unwinding direction, the condition of the skein, that is, the natural position of the thread within the skein has become disturbed to such an extent as to render the subsequent unwinding operation difficult, causing direct and indirect loss of time and material. The same close observation during the work of unwinding the silk from the skeins onto spools shows that due to the absence of a clear indication with regard to the leading end and trailing end of the thread of the skein, the unwinding-operator is liable to attach the leading or beginning end of the thread onto the bobbin or spool instead of the trailing or terminal end of the thread of the skein, thus starting the unwinding of the skein from the inside instead of from the outside part of the skein. Under such circumstances, it is possible for a certain length of time, to draw off the thread from the skein when so starting in reverse order, but it is merely a matter of time when the thread must become broken off. By that

time, the natural condition of the skein, that is the natural position of the thread within the skein has become deranged to such an extent as to again cause unavoidable loss of time to the operator and loss of material, the same as in the case previously cited. The defect in either case, is not limited to the damage mentioned, but the subsequent necessity of knotting the broken ends together automatically causes a deterioration of the quality of the material itself, every knot being equivalent to an imperfection. Therefore, as before stated, it is the primary purpose of the present invention to eliminate the faults of the old method and this is accomplished generally in the following manner: To the terminal or trailing end of the silk thread of the skein I attach an identifying device, such as a heavy, colored cotton or spun silk thread about twelve inches in length and plainly contrasting in color from the color of the silk, such heavy color thread practically forming the end of the skein. That ending-up-thread or identification device is, an elongation of the skein, carried along the center of the skein for a distance of about four inches, once loosely swung or looped around the skein and once more carried along the center outer surface of the skein for a distance of approximately three inches and is there fastened onto the skein by passing the loose end of the identification thread about a small bundle formed from the thread of the skein. It is obvious that the starting or leading end of the thread of the skein may also be attached to this identification thread.

In addition to the foregoing precaution for insuring the proper unwinding of the thread of the skein, I have also provided means whereby the operator may be sure that he has placed the skein on the swift in the same position which it occupied on the large reel on which the skein is originally wound. To accomplish this, I have provided special lacing-bands preferably formed in contrasting colors so that after the lacing-band is placed in position, the operator by noting this band will recognize the position which the skein occupied on the large reel and may then place the skein on the swift in the same relative position.

The two features set forth generally above reduce the waste of the thread and time to a minimum, as the trailing or terminal end of

the thread of the skein may be readily grasped without searching for the same, and the skein may be placed on the swift in such manner that it may be readily unwound.

With the foregoing objects outlined and with other objects in view which will appear as the description proceeds, the invention consists in the novel features hereinafter described in detail, illustrated in the accompanying drawings and more particularly pointed out in the appended claims.

Referring to the drawings:

Figure 1 is a perspective view of a silk skein having the features provided by the present invention.

Fig. 2 is a perspective view of a silk skein arranged on a swift, said skein being laced with a band dyed at its middle portion, and the outer end of the thread being provided 20 with an identifying string or the like.

Fig. 3 illustrates side views of one of the lacing-bands, in one view the lace is shown in the position which it occupies in the skein while in the other view the lace is shown 25 before its application to the skein.

Figs. 4 and 5 illustrate diagrammatically the manner of unwinding the skein onto spools which in Fig. 4 are arranged above the swifts, while in Fig. 5 they are below the 30 swifts.

In the drawing, *a* designates a skein to the trailing or terminal end of which an identifying device *b* is secured, as shown at *c*. This string, which is different from the 35 thread of the skein, either in size, quality or color, has one of its ends secured to the terminal end of the thread of the skein. After the identifying thread is tied to the terminal end of the thread of the skein, it 40 is extended along the outer surface of the skein for a distance of about four inches, then it is looped around the skein and once more carried along the outer surface of the skein for about three inches. The free end 45 of the identifying thread is then loosely tied to a bundle formed by the thread of the skein as shown at *d*. If desired the leading end of the thread of the skein may also be secured to the identifying thread at the portion *d*.

This identifying thread is preferably of a different color from the thread of the skein and now acts in double capacity. It clearly indicates the unwinding direction of the 55 skein and just as clearly indicates the proper, unmistakable ending of the skein, which as far as the unwinding operation is concerned is now the beginning of the skein. The part of the identifying thread which is passed 60 around a bundle formed from the thread of the skein as at *D* will indicate to the operator that the thread of the skein to be properly unwound must be pulled in the direction of the part *d* and away from the knot *c*.

As before stated, the present invention

also includes improvements in the lacing of the silk skein. Heretofore the skein was laced while still on the large reel used in the making of the skein, with a lace-band made of cotton or silk. This band was usually of the same color as the thread of the skein and after the lace was applied and the skein removed from the reel there was no means of advising the operator as to the proper manner in which the skein should be placed on the swift. Further, even if the skein is regularly laid on the swift, it is by no means an easy matter to ascertain the correct position of the swift itself relatively to the winding machine, as the skein heretofore has not been provided with any distinguishable indication to advise the operator as to the proper position of the skein on the swift or of the swift on the winding machine. It is well known that the swift is normally revolved by the tension of the thread itself which is being wound upon a spool or bobbin, and the swift turns in one direction only. Therefore it is very disadvantageous if the skein is not properly placed on the swift or the swift not properly placed on the winding machine.

These inconveniences are entirely removed by the present invention, in which the lacing-bands *g* are dyed at their middle portions as shown at *f* and then the band is folded intermediate its ends as shown at Fig. 3. Each band is placed through the skein on the large reel from left to right so that the skein at its lacing portions has at the opposite sides of its median line a lace of contrasting colors, as shown in Figs. 2 and 3. The lace-band, as illustrated, has a colored portion *f* at the left and a plain portion *e* at its right when winding according to Fig. 5, and vice versa when winding according to Fig. 4, and when lacing-bands of this character are employed, the skein for the purpose of the unwinding operation may be placed upon a swift in the same relative position which it occupied upon the large reel; that is, the colored portion *f* will lie on the left hand side of the swift while the plain portion will be at the right side of the swift when winding according to Fig. 5 and vice versa when winding according to Fig. 4.

As illustrated in Figure 4 the skein *a* at the right hand must be placed on the swift *h*, and the end *d* of the identifying thread has notified the operator that the thread of the skein must be pulled upwardly in order to be wound on the bobbin or spool *i* which is arranged above the swift. The three bobbins and swifts at the left hand side of the right hand swift in Fig. 4 illustrates the manner in which the thread of the skein is unwound from the swift.

Fig. 5 illustrates a similar operation when the skein is to be unwound from the swift onto the bobbin *k* arranged below the swift.

With the use of the present invention, the unwinding-operator is no longer liable to the mistake of mounting the skein on the swift in opposite direction from the proper 5 unwinding-direction and is no longer subjected to mistaking the beginning or leading end of the thread of the skein with the trailing or terminal end of the thread of the skein.

10 In order to render the device effective to the full extent, the winding-operator, after having placed the skein on the swift, and removing the lace or tie-bands, will take hold of the identification thread or end-finder at the point where it is looped around the skein, slightly and carefully pulling it somewhat away from the skein and following it up to the point where it is attached to the real end of the silk thread, breaks off, 20 that is, separates the identification thread from the silk thread and fastens the end of the latter onto the bobbin or spool, without loss of time or loss of material and without having in the least disturbed the natural 25 condition of the skein that is, the position of the thread within the skein.

From the foregoing, it is believed that the construction and advantages of the invention may be readily understood, and it is 30 apparent that various changes may be made in the construction disclosed without departing from the spirit of the invention as expressed in the claims.

I claim:

35 1. A skein of thread having its terminal end provided with an identifying means of different appearance from the thread of the skein to enable a person to grasp the termin-

nal end of the thread of the skein without searching for the latter.

2. A skein of thread provided at its terminal end with a string readily distinguishable from the thread of the skein.

3. A silk skein having its end secured to one end of a string having contrasting characteristics from the thread of the skein, the other end of said string being tied to the skein in such manner that the string may be readily withdrawn.

4. A skein of thread provided with a band laced through the same, said lace-band being of such construction that the portion of the same on one side of the median line of the skein has a different appearance from the portion of the lace-band on the opposite 55 side of said median line.

5. A silk skein provided with a band laced through the same, the middle portion of said band having a different appearance from the remaining portions of the band, and said band being folded intermediate its 60 ends.

6. A method of finishing skeins of thread consisting in tying one end of an identifying string to the terminal end of the thread of the skein, then looping the string around the skein and tying the free end of said string to the thread of the skein.

7. A method of finishing skeins of thread consisting in treating a lacing-band to provide the same with contrasting portions, folding the band intermediate its ends, and lacing said band through said skein.

In testimony whereof he affixes his signatures.

HANS F. HOFER.
